UNITED STATES PATENT OFFICE.

JOSEPH WILLIAM ISHERWOOD, OF CHISLEHURST, ENGLAND.

FLOATING VESSEL.

Application filed October 7, 1924. Serial No. 742,935.

This invention relates to improvements in the construction of floating vessels and has reference to but not exclusively to that class of vessel especially adapted for carrying ore in bulk.

The objects of the invention are to improve the construction of this type of vessel in such manner as to save the cost of the longitudinal stringers usually employed, to provide a construction wherein a less number of parts have to be riveted or dealt with, and in general to provide a seaworthy construction which will be simpler and easier to build and will require a less weight of metal for the same kind and class of vessel than has heretofore been proposed.

With these and other objects in view, the invention consists in the novel details of construction and combinations of parts more fully hereinafter disclosed and particularly pointed out in the claims.

Referring to the accompanying drawings, forming a part of this specification, in which like numerals designate like parts in all the views:—

Figure 1 is a diagrammatic sectional view partially broken away, taken on the line 1—1 of Fig. 3, looking in the direction of the arrows and showing a vessel made in accordance with this invention;

Figure 2 is a sectional view of portions of the bottom of the vessel located on each side of the keel;

Figure 3 is a sectional view partially broken away taken on the line 3—3 of Fig. 1, looking in the direction of the arrows.

1 indicates the sides of the vessel, 2, the bottom plating thereof, and 3 the deck plating of the vessel. Along the upper sides 1 of the vessel, Fig. 1, there are provided above the tops 14 of the wing tanks 10, the relatively deep transverse frames 5 spaced from say 12 to 24 feet apart, and in between these relatively deep and strong transverse frames there are fitted the relatively shallow transverse frames 6'. Below said tank tops 14 there are also fitted the transverse frames 6, so that these said shallow transverse frames 6 and 6' are made to extend respectively from near the bilge 7 up to the tank tops 14 and to the deck portions 3, as shown. For a considerable distance above the bottom tank top 8 there are disposed inner skins 9, forming inner walls of the wing tanks 10 as shown. These inner skins 9 are

supported by the relatively shallow transverse members 13, disposed in line with the members 6; and joining the bottom ends of said members 6 and 13 are large transversely disposed stiffening members or brackets 11, while said members 6 and 13 are joined at their top portions by the stiffening members 12, as shown. 14 represents the tops of the tanks 10, they also serve as deck portions above said tanks. 50 represents extensions of the top 8 of the bottom tank and they constitute the bottoms of said wing tanks 10. These said wing tanks 10 may be made of any suitable and desired length, and are provided with transversely disposed end walls 51 shown as partially broken away in Fig. 1, which end walls are securely fitted to the skins 1 and 9 and to the tank tops 14 and 50, thus constituting said tanks 10 veritable longitudinally disposed box girders of a comparatively inexpensive construction and of great strength. 15 represents brackets connecting the lower portions of the transverses 6' to the tops 14 of the tanks 10. Brackets 16 connect the upper ends of the transverses 6' with the deck 3, while channels or other longitudinal forms 17 support the deck in a manner similar to that disclosed in my prior U. S. Patent #1,029,546, dated June 11, 1912. 18 represents longitudinal stiffening members, disposed on each side of the hatches of the vessel and serving to connect the deck with the widely spaced transverses 5 under the deck, see Fig. 1. 19 represents stiffening members longitudinally disposed in the bottom, see Fig. 2. The bottom shell 2 is further stiffened by the longitudinally disposed channels 20 and the tank top 8 by the longitudinally disposed angle members 21 as used in the well known Isherwood system and disclosed in my said patent above mentioned. 22, Fig. 2, indicates the center keel.

In addition to the foregoing, the bottom is further stiffened by disposing in line with each alternate side frame 6 or in line with each frame 6, the deep transverse members 41, across the bottom as indicated in Figs. 1 and 3.

It will now be clear that this vessel is provided with the above-mentioned deep widely spaced transverses 5 extending under the deck and down each side of the ship to the tank tops 14, and that their stiffening effect is continued into the tanks 10 by the plate members 12; that said vessel has the

relatively deep and widely spaced bottom transverses 41, each alternate one extending across the bottom of the vessel in line with said transverses 5, and that they are continued up beyond the bilges 7 and into the tanks 10 by the plates 11 as shown. It thus results that the vessel in the planes of said deep transverses 5, is completely encircled by stiffening girders, while in between the planes of said transverses 5, there are disposed in the bottom additional transverse members 41, and in the sides the additional transverses 6 and 13. In addition to the above the longitudinal members 19, 20, 21 and 22 are disposed in the bottom and the longitudinal members 17 and 18 in the deck. The outer skin and deck plating are directly attached to the transverse and longitudinal members, and the inner skin plating 9 is likewise attached to the members 11, 12 and 13, so practically all of this plating becomes a part of the longitudinal stiffening. It thus results that the material is so disposed in the hull as to form in effect a plurality of transverse and longitudinally disposed girders, each of which provides a maximum of stiffness with a minimum weight of metal, and therefore a very material saving in metal over the prior ordinary constructions is effected.

In fact, in constructing a vessel according to the foregoing disclosure, should it be about 580 feet long between perpendiculars, I find the upper sections 6' of the transverses 35 may be channels 10 inches deep with $3\frac{1}{2}$ inch flanges, and weighing 22 lbs. per ft., while the lower sections 6 may be 12 inch channels with $3\frac{1}{2}$ inch flanges and weighing 31 lbs. per ft. The members 13 may be of 40 10 inch channels with $3\frac{1}{2}$ inch flanges weighing 22 lbs. per ft., while the plates 11 may be 3 ft. high and 6 ft. long and the plates 12 may be $2\frac{1}{2}$ ft. high and 6 ft. long, and $\frac{3}{8}$ inches thick. 45 The channels 20 may be 10 by $3\frac{1}{2}$ inches weighing 22 lbs. per ft., and the angles 21 may be 7 by $3\frac{1}{2}$ inches, weighing 15 lbs. per foot. The vertical keel 22 may be $5\frac{1}{2}$ ft. deep, weighing 23 lbs. per square foot, and 50 the tanks 10 may be 6 ft. wide and 16 ft. high and about 72 feet long if desired. The longitudinals 19 may be spaced $12\frac{1}{2}$ ft. from the keel and the depth of the longitudinals 18 may be 2 feet, and they may be spaced 55 about 20 ft. on each side of the center line of the ship. The members 17 may be located outside the longitudinals 18 and made of channels having 12 inch webs and 4 inch flanges and weighing about 41 lbs. to the foot. They may be spaced $2\frac{1}{2}$ ft. apart.

A modification at the bilge may be made without departing from the spirit of the invention. Regarding the same, longitudinals 70 are indicated at one side of Fig. 60 1, although if intermediate transverse brack-

ets are fitted between floors 41 at this part in lieu of these three longitudinals, the drawing would appear as shown on the opposite side of said figure.

What is claimed is:

1. A vessel provided with a plurality of strong deep transverse frames and beams spaced from 12' to 24' apart, with a plurality of intermediate and relatively shallow transverse frames spaced on the sides of the vessel between said deep transverse frames, and with wing tanks whose inner walls are spaced from the sides of the vessel a distance equal to the depth of said first named transverse frames, said vessel in its sides being devoid of longitudinally disposed frames but provided with longitudinal frames in its bottom and deck portions.

2. A vessel provided with a plurality of strong deep transverse frames and beams spaced from twelve to twenty-four feet apart with a plurality of intermediate and relatively shallow transverse frames spaced on the sides of the vessel between said deep transverse frames and with wing tanks whose inner walls are provided with vertically disposed stiffening members in line with said shallow frames and are spaced from the sides of the vessel a distance equal to the depth of said first named transverse frames, said vessel in its sides being devoid of longitudinally disposed frames, but provided with longitudinal frames in its bottom and deck portions.

3. A cargo vessel provided with a plurality of strong deep transverse frames and beams spaced from twelve to twenty-four feet apart extending entirely around the deck portions of the vessel with a plurality of intermediate and relatively shallow transverse frames spaced on the sides of the vessel between said deep transverse frames; and with wing tanks whose inner walls are spaced from the sides of the vessel a distance equal to the depth of said first named transverse frames, said vessel in its sides being devoid of longitudinal frames but provided with longitudinal frames in its bottom and deck portions.

4. A cargo vessel provided with a plurality of strong deep transverse frames and beams spaced from twelve to twenty-four feet apart, extending entirely over the deck portions of the vessel, and partially down the sides with a plurality of intermediate and relatively shallow transverse frames spaced on the sides of the vessel between and below said deep transverse frames, and some of which extend across the bottom of the vessel; and with wing tanks whose inner walls are spaced from the sides of the vessel a distance equal to the depth of said first named transverse frames, said vessel in its side being devoid of longitudinally disposed frames but provided with longi-

tudinal frames in its bottom and deck portions.

5. A vessel provided with a plurality of strong deep transverse frames and beams spaced further apart than has been heretofore customary in the same class and size of vessel, with a plurality of intermediate and relatively shallow transverse frames spaced on the sides of the vessel between said deep transverse frames, with wing tanks whose inner walls are spaced from the sides of the vessel a distance equal to the depth of
- said first named transverse frames, the upper ends of said wing tanks receiving the lower ends of said deep transverse frames, 15 said vessel in its sides being devoid of longitudinally disposed frames but provided with longitudinal frames in its bottom and deck portions, and said vessel also provided with a plurality of strong deep transverse frames 20 in said bottom in line with said first mentioned deep transverse frames.

In testimony whereof I affix my signature.
JOSEPH WILLIAM ISHERWOOD.
